AUTOMATIC TELEPHONE APPARATUS

Alfred Boyé, Paris, France

Application May 31, 1933, Serial No. 673,686
In France June 4, 1932

4 Claims. (Cl. 179—90)

This invention relates to a device designed to be utilized in automatic telephony for making calls, which comprises a rotary switch herein-after called the "short circuit switch" movable upon its shaft, which operates when coming in engagement with teeth and the like carried upon stationary crowns in order to set free electric current impulses which are sent in the line by means of a second switch operating at a regular 10 cadence in order to compose the call signal of the station to be connected.

The present apparatus is characterized firstly in that the toothed crowns consist in a plate made in one piece having a circular recess provided 15 on its edge with the teeth required for making up the call signal of the desired station, and with a large opening ending in said recess to allow the passage of a movable device, integral with a runner that controls the movements of the 20 short circuit switch upon its shaft.

Another feature of this invention consists in that the aforesaid plates which are herein-after called the call plates are engaged in vertical parallel slots provided in a box which is removable from the apparatus frame, said box being provided with a front opening which allows its adjustment through a simple sliding movement along the shaft upon which the short circuit switch is mounted, thus allowing the box to be 30 removed without any difficulty, for example for changing the table of the calls, it being then locked in position by means of springs integral with the frame of the apparatus. Each call plate may be provided with two side pawls acting as 35 springs which engage in the horizontal slots in the aforesaid box, so as to lock said plate vertically.

Another feature of the present invention consists in the provision of one or a plurality of supplementary vertical slots which allow of adding 40 one or more call plates and of changing them frequently in order to increase and modify the extent of the table of calls, the slot or slots being formed in a stationary or a slidable part forming the bottom of the aforesaid plate box.

Another characteristic consists in that the short circuit switch and its operating finger are mounted in a kind of drum which is slidably mounted upon a rotary shaft and is provided with a slot. 50 A fork integral with the runner placed upon the upper surface of the apparatus engages said slot.

Still another feature of the invention consists in that the finger operating the short circuit switch is arranged so as to actuate another contact for shortcircuiting the microphone and the 55

receiver when the electric current impulses are sent in the line.

The invention has also for its object a modification in which the apparatus has only one single vertical slot for one single plate which 5 may be replaced at will, this allowing of having a switch which is fixed in the longitudinal direction and also of greatly reducing the size of the apparatus.

The invention has lastly for its object another 10 modification in which the contact of the short circuit switch and the contact for short circuiting the microphone and the receiver are made stationary upon the apparatus and operated by a sleeve concentric with the driving shaft of a part 15 which carries the finger which engages with the teeth provided upon the call plates, said sleeve being provided with notches upon one edge of which said finger acts when it is pushed back by the teeth so as to produce a longitudinal component 20 which causes the sleeve to slide upon the shaft in the required direction for operating the contacts.

The appended drawings show by way of example, one mode of execution of the various modifications of the apparatus hereinbefore mentioned. 25

Fig. 1 is a part sectional view of a first mode of execution.

Fig. 1a is a separate view of the female part 30 of a multiple contact plug for connecting the apparatus with the telephone station.

Fig. 2 is a section taken on the plane A—A of Fig. 1, supposing the switch to have been displaced $\frac{1}{4}$ of a turn relatively to the position 35 shown in Fig. 1.

Fig. 3 is another section taken on the plane B—B of Fig. 1 in the direction of the arrows.

Fig. 4 is a diagram of the electric connections.

Fig. 5 is a side elevation drawn on a smaller 40 scale.

Fig. 6 is a sectional plan view of the modification in which the contacts are fixed upon the apparatus and are driven by a sleeve concentric to the driving shaft.

Referring now to the drawings it will be seen that the apparatus comprises a frame 200 which carries a clockwork motor 201 wound up by depressing a hand lever 202. This movement causes a pinion 201^a keyed upon the motor shaft 201^b to slide under a pawl 201^c integral with a driving wheel 201^d so that when the hand lever is set free the pinion 201^a returning in the opposite direction draws the pawl and the driving wheel 201^d along. This wheel drives by the intermediary of 45 50 55

suitable gears the shaft 203 of a cam 204 which as it rotates at a constant speed opens at a regular cadency a contact 205—206 as shown in Figs. 1 and 4. The wheel 201^a also drives a shaft 207 carried upon the frame and provided with a long extension outside said frame. Four bus-bars 209¹—209², 210¹—210² are fixed between two arms 208 upon said extension these bars being in parallel and located in the same plane that passes through the axis of the shaft 207.

A drum 213 is slidably secured upon the shaft 207, and a radial finger 214 slidably mounted in a boss of said drum, is forced outwards by two spring blades 215¹, 216¹ of which the first constitutes with another blade 215² the short circuit switch, the second constituting with another blade 216² the switch designed for shortcircuiting the microphone and the receiver during the call. When inoperative, the contact 215¹—215² is closed 20 and the contact 216¹—216² is open.

These blades are all adjusted in the drum 213 and by their extremity opposite to the contact are in frictional engagement as follows:

The blade 215¹ upon bar 209¹, blade 215² upon bar 209², blade 216¹ upon bar 210¹ and blade 216² upon bar 210²; the four bars 209¹, 209², 210¹, 210² passing through a large opening 213¹ in said drum. As they rotate with the shaft 207, the bars frictionally engage with four concentric crowns 217¹, 217², 218¹, 218² embedded in, the outer wall of frame 200.

Considering the diagrammatic view in Fig. 4, it will be seen that said crowns are connected by wires 219¹, 219², 220¹, 220² to the four plugs b¹, b², b³, b⁴ of a male contacting element 221, the female element of which carries four contact pieces a¹, a², a³, a⁴. The contact pieces a¹, a² are mounted in series in the telephone line L through the conductors 223¹—223², and the contact pieces a³, a⁴ are shunted at the terminals of the microphone M and of the receiver R through the conductors 224¹, 224².

It will also be seen in Fig. 4 that the contact piece 205—206 actuated to produce the opening through the cam or breaking device 204 is shunted upon the conductors 219¹, 219² and therefore relatively to the short circuit switch 215¹, 215² and vice versa. When the apparatus is inoperative, both contact pieces 205—206 and 215¹—215² are closed.

Referring again to Figs. 1, 1a, it will be seen that the male contacting element 221 is secured upon one side of the frame, and that the female part 222 is removable and is connected with the station through the conductors 223¹, 223², 224¹, 224².

The contact pieces a¹, a² which are materially constituted by blades and are provided with pins c¹, c² which enter in the block 222 and engage the grooves d¹, d² of the corresponding plugs b¹, b² when in their position of engagement are maintained by said pins out of contact with a small conducting bar e. On the contrary, when the female part is taken out, said contact pieces engage the small bar e and in this manner the interruption in the line between a¹—a² disappears and the station is restored to its normal state, the contact pieces a³, a⁴ being shunted and having no longer any action to perform.

In this mode of execution the call plates 225 are made in one piece provided with a middle recess 225^a carrying along its edge an interrupted row of teeth designed to force back the finger 214 in order to open the contact 215¹, 215² so that

the interruptions produced by the cam 204 which opens the contact 205—206 are felt along the line. Consequently the row of teeth comprises several portions each extending upon an arc of a circle having a predetermined length in function with the number of interruptions to be allowed. In Paris for instance where the teeth in each plate comprise 7 arcs of a circle corresponding to three letters and four digits required for making up the call signal of the called station, 10 for example TRU 52—91, there is one plate for every station to be called and the apparatus comprises for instance 50 plates composing the table of the calls most frequently asked by the user. These plates are inserted in vertical slots 226 following one another made in a box 227 which is also provided upon its sides with two horizontal slots 228. The plates are each provided with two suitable pawls 229 which when at rest before being engaged by the groove 226 are slightly deviated relatively to the plane of the plate. When the plate reaches the end of its stroke in its slot the pawls 229 which are in the horizontal slots 228 return to their inclined position thus preventing the vertical displacements of the plate. 25

The plates are adjusted in the box 227 before mounting the same upon the apparatus; they are provided with a wide notch 230 ending in the recess 225^a which allows of putting it in position by moving it lengthwise upon a bed 200^a 30 of the frame 200, the recess 225^a being of a suitable size to allow the passage of the drum 213, the notch 230 being also sufficiently large to allow the passage of the body of a runner 231 which by the intermediary of a fork 231^a entering in a groove 213² in said drum, serves to move the latter and consequently the short circuit switch. When the box has been completely engaged it is locked in position by springs 232 mounted upon the frame 200 by means of pins 233 which engage a vertical slot 234 in said box as will be seen in Figs. 1 and 5.

A part 235 presenting a bearing surface 236, for the end of the shaft 207 is removably mounted in any suitable manner at the end of the box 45. 227. This part is also provided with a groove 237 which allows the adjustment of any supplementary call plate which is not recorded in the ordinary table of calls. This call plate will be taken from a case in which the user keeps in 50 store a certain number of plates corresponding to calls that are seldom asked for. The user may however have a plurality of boxes 227 for different classes of callers; customers, tradesmen, etc.

The box 227 is also provided with a horizontal plate 238 (Fig. 5) forming a cover which is slit to allow the movement of the runner 231 which carries the table of the telephone subscribers corresponding to the various call plates contained in said box. The runner is provided with indexes 60 239 which allow of stopping exactly upon the various marks drawn upon the plate 238.

The mode of operation is as follows:

The operator takes hold of the runner knob 65 231 and brings it over the mark which indicates the call plate corresponding to the desired call. He then depresses the hand lever 202 the shaft 201^b of which carries a crown provided with an adjustable abutment 240 which raises the lever 70 241 that previously locked the shaft 207 by means of a pin 242 engaged in the notch 243 of a disk 244 mounted upon said shaft 207 and locking the cam 204 by means of a projection 245.

When the operator releases the hand lever the 75

clockwork motor transmits its movement to the shaft 207 and the cam 204 which rotating at a constant speed owing to a speed regulator 246, opens at a regular cadency the contact 205—206. 5 The drum 213 being drawn by the shaft 207, the finger 214 comes in engagement with the teeth 225^b of the call plate and is pushed inside. Consequently the finger 214 closes the contact 216¹—216² which short-circuits the microphone and the receiver and opens the contact 215¹—215², so that according to the length of the row of teeth upon which said finger passes, a certain number 10 of interruptions and electric current impulses, caused by the operation of the contact 205—206 15 are produced in the line. The finger 214 thus passes over the various portions of the row of teeth (7 for Paris as already mentioned) making a complete turn equal to one revolution at the end of which the preliminary operations before obtaining the connections are ended. Before the end of this turn the abutment 240 frees the lever 241 which under the action of its return spring 241, locks the disc 244 and the cam 204 as soon as the turn is ended.

20 25 It will easily be understood that the apparatus could be reduced so as to comprise one slot only for one single removable call plate, which would be taken from a separate case. The short circuit switch would then be fixed in the longitudinal direction and the runner as well as the fork would not be necessary. The aforesaid slot could then be made in a projection of the frame itself, the box 227 being omitted.

In a modified mode of execution shown in Fig. 35 6, the shaft 201 is provided with a concentric sleeve 248 which may slide by means of a key 249 engaged in a slot provided in the sleeve. The latter carries at one end a crown 250 which, when the sleeve slides upon the shaft compresses 40 the spring 251, thus opening the contact 215¹—215² and closing the contact 216¹—216². A part 252 provided with a slot 253 which may be moved by means of a fork in the same manner as the drum 213 in the apparatus previously described is engaged upon the sleeve 248. This part 45 252 is caused to rotate with the sleeve 248 by any suitable means. A long rod 254 integral with the crown 250 and passing through the part 252 may be provided to this end. A small radial cylinder 50 255 in which a finger 256, substituted for the finger 214 in the previously described apparatus is secured upon the part 252. The finger 256 is acted upon by a spring 257 designed to cause the outer end of said finger to project out of the cylinder. Its other end is suitably bevelled at 55 256¹ and, when inoperative is always opposite a notch 248¹ in the sleeve 248 but its back edge is slightly out of position relatively to the edge of said notch, so that when the teeth 225^b of a call plate 225 engage the finger 256 as the latter rotates and forces it back, the bevel 256¹ will press upon the notch 248¹ and cause it to move slightly back. The sliding of the sleeve which results will cause the above mentioned operations 60 to take place, i. e. the opening of the contact 215¹—215², and the closing of the contact 216¹—216² which have the same functions as in the apparatus first described.

This new mode of execution will have the important advantage of avoiding the use of the bars 209¹—210² and of the crowns 217¹—218² and consequently of every frictional contact.

What I claim and desire to secure by Letters Patent of the United States is:

75 1. An apparatus for making calls in automatic

telephony, comprising a frame, a rotary shaft carried by said frame, a switch slidable with respect to said shaft and rotatable therewith, a box carried by said frame, a plurality of parallel plates situated within said box, each plate being provided with a central opening and a notch permitting the passage of said switch through the plate, the longitudinal axis of said shaft coinciding with an axis passing through the middle of the central openings, each plate being provided 10 with teeth formed on the circumference of the central opening and adapted to engage said switch, the teeth of each plate being adapted to actuate said switch a predetermined number of times to call a station corresponding to a certain plate, an interrupter adapted to be rotated at a constant speed, and a contact interposed in a telephone line and actuated by said interrupter, the terminals of said switch being shunted with respect to the terminals of the last-mentioned contact.

2. An apparatus for making calls in automatic telephony comprising a frame, a rotary shaft carried by said frame, a switch slidable with respect to said shaft and rotatable therewith, a box carried by said frame and having a plurality of parallel slots, a plurality of plates, each plate being situated in a separate slot, said box being provided with at least one longitudinal slot intersecting the first-mentioned slots, at least one 30 separate pawl carried by each plate and adapted to engage the last-mentioned longitudinal slot, each plate being provided with a central opening and a notch permitting the passage of said switch through the plate, the longitudinal axis of said 35 shaft coinciding with an axis passing through the middle of the central openings, each plate being provided with teeth formed on the circumference of the central opening and adapted to engage said switch, the teeth of each plate being adapted 40 to actuate said switch a predetermined number of times to call a station corresponding to a certain plate, an interrupter adapted to be rotated at a constant speed, and a contact interposed in a telephone line and actuated by said interrupter, 45 the terminals of said switch being shunted with respect to the terminals of the last-mentioned contact.

3. An apparatus for making calls in automatic telephony, comprising a frame, a rotary shaft 50 carried by said frame, a drum keyed upon said shaft and slidable with respect thereto, a fork-shaped member engaging a slot formed in said drum, a runner-knob integral with said member and adapted to move said drum with respect to 55 said shaft, a switch carried by said drum, a box carried by said frame, a plurality of parallel plates situated within said box, each plate being provided with a central opening and a notch permitting the passage of said switch, said drum and 60 said runner-knob through the plate, the longitudinal axis of said shaft coinciding with an axis opening through the middle of the central openings, each plate being provided with teeth formed on the circumference of the central opening and 65 adapted to engage said switch, the teeth of each plate being adapted to actuate said switch a predetermined number of times to call a station corresponding to a certain plate, an interrupter adapted to be rotated at a constant speed, and a 70 contact interposed in a telephone line and actuated by said interrupter, the terminals of said switch being shunted with respect to the terminals of the last-mentioned contact.

4. An apparatus for making calls in automatic 75

telephony, comprising a frame, a rotary shaft carried by said frame, a switch slideable with respect to said shaft and rotatable therewith, a driving finger connected with said switch, a removable and replaceable plate carried by said frame, said plate being provided with a central opening and having teeth formed on the circumference of said opening and adapted to operate

said finger a predetermined number of times to call a station corresponding to said plate, an interrupter adapted to be rotated at a constant speed, and a contact interposed in a telephone line and actuated by said interrupter, the terminals 5 of said switch being shunted with respect to the terminals of the last-mentioned contact.

ALFRED BOYÉ.
